UNITED STATES PATENT OFFICE.

WILLIAM N. MANUEL AND EMILIO PASCUCCI, OF CORNING, NEW YORK, ASSIGNEES
TO CORNING GLASS WORKS, OF CORNING, NEW YORK, A CORPORATION OF NEW
YORK.

DESIGN FOR A COMBINED FRESNEL AND PLAIN LANTERN-GLOBE.

57,984.

Specification for Design.

Patented May 24, 1921.

Application filed November 3, 1920. Serial No. 421,601. Term of patent 14 years.

To all whom it may concern:

Be it known that we, WILLIAM N. MANUEL and EMILIO PASCUCCI, citizens of the United States, residing at Corning, in the county of Steuben and State of New York, have invented a new, original, and ornamental Design for Combined Fresnel and Plain Lantern-Globes, of which the following is a specification, reference being had to the accompanying drawing, forming part hereof.

The figure is an elevation of a combined Fresnel and plain lantern globe showing our design.

We claim:

The ornamental design for a combined Fresnel and plain lantern globe, as shown.

WILLIAM N. MANUEL.
EMILIO PASCUCCI.
